UNITED STATES PATENT OFFICE.

ROBERT STOCK, OF SANDUSKY, OHIO.

DESIGN FOR A WHEEL FOR VEHICLES.

56,712.

Specification for Design.

Patented Nov. 30, 1920.

Application filed February 24, 1920. Serial No. 361,001. Term of patent 7 years.

To all whom it may concern:

Be it known that I, ROBERT STOCK, a citizen of the United States, and resident of the city of Sandusky, in the county of Erie and State of Ohio, have invented a new, original, and ornamental Design for a Wheel for Vehicles, of which the following is a specification, reference being had to the accompanying drawing, forming part thereof.

An embodiment of my new design for a wheel for vehicles is shown in the accompanying drawing, which represents a side elevation of the wheel.

I claim:

The ornamental design for a wheel for vehicles, substantially as shown.

ROBERT STOCK.
